UNITED STATES PATENT OFFICE.

JOHN THOMSON, OF BROOKLYN, NEW YORK.

COMBINED BELT-SHIFTING AND BRAKE APPARATUS.

SPECIFICATION forming part of Letters Patent No. 427,449, dated May 6, 1890.

Application filed March 14, 1890. Serial No. 343,900. (No model.)

To all whom it may concern:

Be it known that I, JOHN THOMSON, a citizen of the United States, residing at Brooklyn, Kings county, State of New York, have 5 invented certain new and useful Improvements in Combined Belt-Shifting and Brake Apparatus, of which the following is a specification.

This is an invention in apparatus for shifting the belt and stopping the fly-wheel by a single movement of a lever, and is particularly intended for and applicable to printing, stamping, or embossing machinery. The object thereof is to obtain an inexpensive but efficient, quick, and powerful action with such a construction and disposal of the parts as to be readily adaptable to existing types of machinery and to the various conditions met in practice.

20 In the drawings, Figures 1 and 2 are respectively side and front elevations of a fly-wheel with tight and loose pulleys attached thereto, showing the application of my improvement; and Fig. 3 is a top plan view of the 25 hand-lever and the brake-shoe.

In the apparatus of this description the efficiency and usefulness largely depend upon the convenience for adjustment and the permanency and durability of the structure. It 30 should be readily adaptable to fly-wheels and pulleys of different diameters turning in either direction and to the requirements of individual operators.

In the illustration the fly-wheel 95 may be 35 assumed as revolving from the operator, in which instance the pulling side 96 of the belt is in front; hence it may be shifted or shipped from the opposite or following side. In the two standards 97, each a duplicate of the 40 other, which may be directly secured to the floor or the base of the machine, is mounted a piece of shafting 98. To the backward end of this is secured the belt-shifting fork 99, properly engaging the belt. To the forward 45 end of the shaft is likewise secured the hand-lever 100. By vibrating the hand-lever acting through the shaft to the fork the belt will be shipped from the tight pulley 101 to the loose pulley 102, or vice versa. From the 50 hub of the hand-lever a short arm 103 extends (like a bell-crank) out under the fly-wheel, the extremity of which is formed to approxi-

mate a sphere or ball 104. Upon this ball is mounted a brake-shoe 105, properly adapted thereto by a socket-bearing, half in the lower 55 side of the shoe and half in the cap 106, secured thereto, as by the screws 107. In the face of the shoe two recesses are formed, into which are snugly forced pieces of semi-elastic material 108—such as leather, paper, rubber, 60 or wood—but which project above the face of the shoe; hence it will be apparent that when the hand-lever is forced over toward the position 109 the material in the face of the shoe will be brought into contact with the 65 face of the fly-wheel, and that the universal action permitted by the ball-and-socket connection between the shoe and the lever will permit and insure a prompt and automatic adjustment of the contacting surfaces. In 70 applying this apparatus to a machine the workman is not required to make a close adjustment. The standards are first brought to an approximate position and secured. The handle is then forced over to position 109, 75 which is limited or determined by the impact of the shoe against the face of the fly-wheel. The belt-shifting fork is next swung on the shaft and secured, as by the set-bolt 110, to bring the belt over to the desired extent upon 80 the loose pulley. The handle is then reversed as to position 111, the throw of the belt-shifting fork being determined in this instance by the adjusting-bolt 112 in the short arm of the lever, which makes contact upon the face of 85 the standard.

In the fitting of the ball and socket no difficult or accurate operations are necessary, as by simply inserting rubber or leather washers under the screws which secure the socket-cap the shoe is held with sufficient friction to prevent it from swinging loosely, while at the same time its correct automatic adjustment to the face of the fly-wheel is freely permitted.

If the direction of the revolution be reversed from that shown in the drawings then 95 it is simply necessary to set the belt-shifter fork forward to the position indicated by dotted outline 113. The device may also be readily operated by a pedal, as indicated by 100 dotted outline 114.

Without limiting myself to the precise construction of parts shown, I claim—

The combination, with the standard and a

rocking shaft mounted thereon, of a belt-shifter fork and hand-lever connected to the rocking shaft, the hand-lever having a right-angled projection, upon the extremity of
5 which is mounted, by means of a universal joint, a brake-shoe, substantially as described.

In testimony whereof I have signed my

name to this specification in the presence of two subscribing witnesses.

JOHN THOMSON.
